UNITED STATES PATENT OFFICE

ISAAC A. BAUM, OF CHICAGO, ILLINOIS

METAL CORNER CONNECTION

Application filed October 14, 1929. Serial No. 399,619.

My invention relates to building construction and more particularly to corner connections for intersecting metal frame members, similar in some respects to that shown in my 5 prior Patents No. 1,723,991 of August 13, 1929, and No. 1,747,415 of February 18, 1930.

In building construction, the use of metal frames for door and window openings has become a very common expedient and possesses a number of distinct advantages over 10 the wood, and wood and metal constructions heretofore utilized.

However, considerable difficulty has been experienced in suitably joining the separate 15 members constituting the opening frames at their intersections. A number of devices have been presented to the trade which are intended to obviate the objections heretofore experienced but the proposition of insuring 20 against separation of rigid intersecting elements in a simple and economical manner has been heretofore unsolved.

One of the objects of my invention is to 25 provide a corner connection for intersecting metal frame members which consists substantially of a bendable length of wire, which does not interfere with the interfitting features of the frame members, and yet will insure a positive securing means to prevent 30 separation of the frame members.

Another object of my invention is to provide a construction which will permit the use and reception of a short length of wood block for nailing purposes when the frames 35 are originally set. Obviously the setting of metal frame members presents similar difficulties to the workmen and the incorporation of a wood block near the upper extremity of the vertical members provides a necessary 40 and useful nailing means.

My invention will be more fully understood by reference to the accompanying drawings, in which

Fig. 1 is an end elevation of a device such 45 as contemplated herein;

Fig. 2 is a side elevation showing the various parts of my invention in dotted lines;

Fig. 3 is a plan view partly in section showing my device and the use of a block there- 50 in; and

Fig. 4 is a sectional elevation showing a modified form of my invention.

Obviously the two sides of the opening frame are reversed duplicates and therefore only one side is herein illustrated.

As seen in the drawings, my invention comprises substantially the channel shaped header 10 and the vertical channel shaped members 11 constituting the opening frame. The members 10-11 are of channel shape and have rebent plaster terminals 12-13 formed thereon. The vertical and header members are also bent to form the door stops 14, 15. As best seen in Fig. 3 a portion at the upper extremity of the flanges 16, 17 of the vertical member is struck out to form the tongues 18-19 which are bent inward and lie in a plane substantially parallel to the web 20 of the vertical member 11. The header member 10 is provided with a pair of downwardly extending angle plates 21, 22 which provide a sliding interfitting connection with the vertical member 11. There is also provided a channel shaped connecting strip 23 which joins the angle plates 21, 22 of the header 10. The member 23 is adapted to be so placed so that the upper margin thereof will register with the upper margin of the tongues 18, 19 when the two members are slid into position.

As best seen in Fig. 3 I have provided short lengths of bendable wire A which are suitably connected to the front face of the tongues 18, 19. These wires are welded to the tongues at the plant and stand in a vertical position such as shown in Fig. 1 when the members are joined. Thereafter, the wire is bent over the upper margin of the member 23 thus preventing the separation of the members. As seen, the connecting wires are of a very simple form and require merely a few blows of a hammer by the workman to firmly join the intersecting members.

My invention also contemplates the insertion of the block 24 in the space between the tongues 18, 19 and the web 21 of the vertical member. The block is suitably held in place by nails 25 passing through registering apertures in the tongues 18, 19 and member 23.

I have shown a modified form of my invention in Fig. 4 which contemplates the use of the nail 26 driven into the block 24 and bent over the registering margins of the members 18, 19 and 23.

5 It is thus seen that I have provided a simple expedient for joining two rigid intersecting metal frame members in a very simple and time-saving manner. The wires as stated 10 are secured at the factory when the members are fabricated and the members need only be slid into position and the wires bent over to insure against separation either laterally or vertically.

15 I claim:

1. In frame construction, the combination of vertical and horizontal intersecting channel-shaped frame members, one of said members having tongues cut out of its flanges 20 and bent inwardly into the plane of the web of said member, a pair of angle plates secured to the other frame member, a member joining the free portions of said plates, said member positioned to lie alongside of said 25 tongues, and a length of bendable metal carried by the first mentioned frame member and adapted to be bent over the plate-joining member when the parts are in final position.

2. A corner connection for intersecting 30 metal frame members comprising a vertically disposed, channel-shaped member, tongues formed out of the flanges thereof, said tongues being bent inwardly to lie parallel with the web of said member, a second channel shaped member adapted to slidably interfit with said first member, and a strip of wire 35 on said tongues adapted to be bent over to securely hold said frame members against separation.

40 3. A corner connection for intersecting metal frame members comprising a vertically disposed, channel shaped member, tongues formed out of the flanges thereof, said tongues being bent inwardly to lie parallel 45 with the web of said member, a second channel shaped member adapted to slidably interfit with said first member, a metal strip joining the flanges of said second member, the top margin thereof being adapted to register 50 with said tongues, and a strip of wire on said tongues adapted to be bent over to securely hold said frame members against separation.

55 4. A corner connection for intersecting metal frame members comprising a vertically disposed channel shaped member, tongues formed out of the flanges thereof, said tongues being bent inwardly to lie parallel 60 with the web of said member, a second channel shaped member adapted to slidably interfit with said first member, a wood nailing block in said first mentioned member located between said tongues and the web of said member, and a strip of wire on said tongues.

adapted to be bent over to securely hold said frame members against separation.

5. Means for joining intersecting metal frame members, comprising a vertically disposed, channel shaped member, tongues 70 formed from said flanges and bent inwardly to lie parallel with the web of said member, a wood nailing block located between said web and said tongues, a second channel shaped member adapted to slidably interfit 75 with said first mentioned frame member, a metal strip joining the flanges of said second member, the top margin thereof being adapted for registering contact with said tongues, and a strip of wire projecting vertically from 80 said tongues, said wire being adapted to be bent over said joining strip to secure said frame members against separation.

In testimony whereof I have affixed my signature:

ISAAC A. BAUM.
